(57) **CLAIM**

I claim the ornamental design for an nasal dilator with relief cuts, as shown and described.

DESCRIPTION

FIG. 1 is a top plan view of a first embodiment of a nasal dilator with relief cuts according to my invention;

FIG. 2 is a perspective view thereof;

FIG. 3 is a perspective view thereof, shown in a slightly flexed state;

FIG. 4 is a perspective view thereof, shown in a state of use;

FIG. 5 is a top plan view of a second embodiment of a nasal dilator with relief cuts according to my invention;

FIG. 6 is a perspective view thereof;

FIG. 7 is a perspective view thereof, shown in a slightly flexed state;

FIG. 8 is a perspective view thereof, shown in a state of use;

FIG. 9 is a top plan view of a third embodiment of a nasal dilator with relief cuts according to my invention;

FIG. 10 is a perspective view thereof;

FIG. 11 is a perspective view thereof, shown in a slightly flexed state;

FIG. 12 is a perspective view thereof, shown in a state of use;

FIG. 13 is a top plan view of a fourth embodiment of a nasal dilator with relief cuts according to my invention;

FIG. 14 is a perspective view thereof;

FIG. 15 is a perspective view thereof, shown in a slightly flexed state; and,

FIG. 16 is a perspective view thereof, shown in a state of use.

The broken line showing of human facial features is directed to environment and is for illustrative purposes only; the broken lines form no part of the claimed design.
